UNITED STATES PATENT OFFICE.

JOHANN MAINZER, OF SOEST, GERMANY.

BOTTLE-BLOWING MACHINE.

1,232,353.

Specification of Letters Patent.

Patented July 3, 1917.

Application filed February 18, 1914. Serial No. 819,351.

To all whom it may concern:

Be it known that I, JOHANN MAINZER, subject of the German Emperor, residing at Soest, Germany, have invented certain new 5 and useful Improvements in Bottle-Blowing Machines, of which the following is a specification.

This invention relates to an independently operating bottle blowing machine having several preliminary and finishing blowing molds mounted on one single table. 10 Bottle blowing machines are already known, which operate with several head, preliminary and finishing blowing molds but they are mainly dependent on large mechanical auxiliary plant such as compressors, vacuum pumps, etc. They can however only be employed in connection with special melting furnaces and are also adapted only for making 15 large quantities and special bottles.

Now according to the machine forming the subject matter of this invention, it is possible to make any shape of bottle and also different shapes of bottles simultaneously without special melting and compressor plants, etc., being necessary. The bottles are made absolutely automatically except that a workman must introduce the 25 liquid glass mass.

30 The essential features of the herein described machine are that all movements of the various parts effecting the formation of the glass bottle, such as the opening and closing of the preliminary and finishing molds, the swinging out, opening and closing of the head mold, the lowering and raising of the closing lids and blowing heads, the cutting off of the liquid glass, the insertion of the core, the movement of the 35 pistons in the suction and pressure cylinders as well as the discharge of the finished bottle from the finishing mold are effected by cam disks which are mounted on one single driving shaft of the machine and act 40 on lever and wheel mechanisms by means of rollers. The machine may be driven by motor, belt, worm or the like. One single machine may be driven, or two pairs coupled side by side in battery form, or 4 or more 45 machines arranged around a column like a whirligig.

The invention is shown in the accompanying drawings by way of example.

Figure 1 is a front elevation of a single 55 machine;

Fig. 2 is a plan view of the machine;

Fig. 3 is a horizontal section according to the plane 3—3 of Fig. 1 and shows the driving shaft with the cam disks;

Fig. 4 is a vertical section through a 60 four-armed machine, the details being however omitted:

Fig. 5 is a plan of the frame of a four-armed machine according to Fig. 4;

Fig. 6 is a longitudinal vertical section 65 through a single machine according to the plane 6—6 in Fig. 2;

Fig. 7 is a plan view of the cutting off device;

Fig. 8 is a longitudinal vertical section 70 through the machine according to the plane 8—8 in Fig. 2 and

Fig. 8^a shows a longitudinal section through the adjustable pivot 49 of Fig. 8;

Fig. 8^b is a side elevational view, partly 75 in section, of the pivot 49 and appurtenant parts.

Fig. 8^c is a longitudinal section on the line c—d of Fig. 8^a;

Fig. 8^d is a front elevation of the pivot 80 from the other side, partly in section;

Fig. 9 is a longitudinal vertical section according to the plane 9—9 in Fig. 2;

Fig. 10 is a longitudinal vertical section according to the plane 10—10 in Fig. 2; 85

Fig. 11 shows a view of the head mold with its closing device and

Fig. 12 is a plan of the frame of the head mold.

Each individual machine consists of an 90 upper table 1 and a lower table 2, which are secured together by intermediate pieces 3 (see Fig. 4) and by a bushing 4. The bushing 4 is rotatably mounted on the standard or central column 5, around which the 95 single machines are situated. For facilitating the rotation, ball bearings 6 and 7 are also fitted above and below between the bushing 4 and the column 5. On the lower part of the column 5 is mounted a conical 100 toothed rim 8, which engages with each bevel wheel 9 of a machine. On the lower table 2 of each machine is provided a bearing block 10, adapted for receiving one of the pins 13 of the axle of the bevel wheels 105 9 while the other pin is mounted in the bushing 4. A worm wheel rim 11 is secured to the bearing blocks 10 and a worm 12 mounted on the frame of the column 5 engages in the said rim (Fig. 4). By the 110 driving of the worm 12, the worm wheel rim 11 and also the tables 1 and 2, etc., of the

machine are set in rotation, so that the tables move around the central column 5.

The bevel wheels 9 are also provided with a front toothed wheel rim 9^a. The toothed rims 9^a mesh with the intermediate wheels 14, which are mounted on the intermediate pieces 3 of the tables 1 and 2. A shaft 16 is mounted between the tables and a toothed wheel 15 is mounted on the shaft and engages with the intermediate wheel 14. By the rotation of the bevel wheels 9, the shaft 16 mounted in each machine will also be set in rotation.

If a machine arm is driven separately, the toothed wheels 15 and 14 will be dispensed with. In substitution thereof, the shaft 16 is extended outward and a pulley 150 (Fig. 2) or a worm wheel is mounted thereon. The machine may then also be provided with running wheels 151, as shown in Figs. 1, 3 and 8-10.

On the shaft 16 of each individual machine are mounted a number of cam disks 17-26 (Fig. 3) by which the different movements of the molds and other parts of the machine are effected, the disks being adapted to operate the parts as follows:

The cam disk 17 is adapted to operate the piston 103 (Fig. 10) by which the finishing blowing of the bottle is effected.

The movement of the closing lid 60 (Fig. 1) of the preliminary mold is effected by the disk 18.

The disk 19 operates the blowing head 113 (Fig. 1).

The disk 20 effects the swinging movement of the head mold 47 (Fig. 2).

The disk 21 effects the closing and opening movements of the head mold 47 (Fig. 11).

The disk 22 is adapted to operate the core rod 45 (Fig. 6).

The preliminary mold 41 (Fig. 2) is closed by the disk 23.

The disk 24 is adapted to operate the suction piston 52 (Fig. 8) and the cutting off knife 96, 97 (Figs. 6 and 7) and also to open the preliminary mold.

By means of the cam disk 25, the finished bottle is removed from the finishing mold.

The disk 26 effects the closing and opening of the finishing mold 75 (Fig. 2).

The operation of the various cam disks and the mechanism in connection therewith are hereinafter fully described.

By the rotation of the shaft 16 with the superposed cam disk 23 (see Fig. 6) a roller 28 is driven, which is adjustably mounted on a lever 29 keyed upon the shaft 30. If the disk 23 with its abutment 23^a abuts the roller 28, the latter will be shifted laterally to the height of the abutment, whereby a rotation of the shaft 30 with the lever arms 31 and 32 secured thereon takes place (see Figs. 6 and 2). Rods 33 and 34 are connected to

the upper ends of the lever arms 31 and 32 by the interposition of balancing springs 34^a, such rods being also connected to cranked levers 35 and 36 (Fig. 2). The cranked levers 35 and 36 are rotatably mounted on pins 37 and 38 secured to the machine frame and engage with their free ends, through the medium of intermediate pieces 39 and 40 (Fig. 2), the halves of the two-part, adjustable preliminary mold 41. The preliminary mold 41 will therefore be closed by the above-mentioned rotation of the shaft effected by the cam disk 23.

At the same moment, the abutment of the cam disk 22 (Fig. 6) has depressed the roller 42 of the double-armed lever 43 adapted to rotate on the pin 44, whereby the lower arm of the lever 43, which is connected to the vertical core rod 45 (Fig. 6) will be moved upward, so that the neck core 46 (i. e., the calibrated core determining the neck opening of the bottle) mounted on the core rod 45 must enter the head mold 47 and preliminary mold 41.

The disk 24 (Fig. 8) mounted on the shaft 16 is provided with a groove (Fig. 3) wherein a roller 48 runs, which is mounted on the cranked lever 50 adapted to oscillate on the adjustable pin 49. As soon as the neck core 46 enters the head mold 47 (Fig. 6), the roller 48 (Fig. 8) will be drawn inward to the shaft 16 by the rotation of the disk 24, whereby the lever 50 will be rotated. The free arm of the lever 50 is connected to the piston rod 51 of the suction piston 52, so that by the oscillation of the lever 50, the piston 52 will be reciprocated in the cylinder 53 secured to the machine frame. The cylinder 53 is connected to the core casing 54 (Fig. 6), by a channel, so that a vacuum is produced in the core casing 54 by the downward movement of the piston 52. Since the preliminary mold 41 is connected directly to the core casing, the suction of the piston 52 will cause the liquid glass in the preliminary mold 41 to be sucked or drawn around the core 46.

A vertical lever 89 (Fig. 6) is connected to the lower table 2 of the machine and the free end of the said lever arm is connected on both sides with the connecting rods 90 and 91 (see Fig. 7). The rods 90 and 91 engage with the knife levers 92 and 93, which are adapted to oscillate on a pin 94. The free arms of the levers 92 and 93 are made in the form of knife edges 96 and 97. If, through the rotation of the shaft 16, the disk 24 bears with its cam 95 (Fig. 6) against the projection 89^a of the lever 89, the lever 89 swings out and consequently, the knife levers 92 and 93 also make a swinging movement and cut off the glass ball from the ladle or the gathering iron used by the workman. For the purpose of automatically returning the knives 96 and 97 to their posi-

tion of rest, there is connected to the lever 89 (Fig. 6) a spring 98, whose other end is attached to the table 1. The knife lever 93 has an extension in the form of a handle 93^a 5 (Fig. 7) so that the workman can also cut off the ball of glass by hand.

When the piston 52 (Fig. 8) has reached its low position, the roller 42 leaves the abutment of the disk 22 (Fig. 6) and the core 10 carrier 45 with the core 46 returns through its own weight to its position of rest.

At the same time, a roller 56, which is mounted on a cranked lever 58 will be shifted by the cam disk 18 (Fig. 10) the said lever 15 being adapted to oscillate on a pin 57 mounted on the table 2 of the machine. The free end of the lever 58 is connected by a vertical rod 59 (Figs. 10 and 1) to the double lever 61 carrying the closing lid 60 20 (Fig. 1) of the preliminary mold. The lever 61 oscillates on the pin 61^b of a stationary vertical column 61^c and is adjustably connected with its free end to the vertical rod 60^a which carries the closing lid or cover 60 25 of the preliminary mold. For effecting a parallel motion, a second lever arm 61^a is provided between the rod 60^a and the column 61^c. By the action of the roller 56 of the lever 58 (Fig. 10) and rod 59, the lever arms 30 61 and 61^a can therefore be brought into a horizontal position, the lid or cover 60 being firmly fixed on and closing the preliminary mold 41.

The disk 24 (Fig. 8) has meanwhile rotated to such an extent that the roller 48 is 35 forced outward, so that through the medium of the lever 50, the piston 52 (Fig. 8) will be forced into its highest position and consequently the previously drawn in air will be 40 let into the cavity left behind by the neck core 46 in the glass, whereby the preliminary blowing of the bottle takes place.

Provision has been made for a special 45 regulating device (shown in Figs. 8 and 8^a) whereby neither too much nor too little air is preliminarily blown in the preliminary mold, for otherwise the efficiency of the machine and also the quality of the bottles would be materially affected. For regulating 50 purposes, an adjustability of the pivot 49 and the engaging position of the roller 48 of the lever 50 is provided for.

For this purpose, the bushes 143 and 144 are placed over the pivot 49, the lever 50 being 55 rotatable on the bush 144, while the bush 143 can be moved in a longitudinal slot 49^b of a bearing 49^a secured to the frame of the machine. The flanges 180 and 181 of the bushes bear on both sides against the front 60 faces of the bearing 49^a so that when tightening the screw 145 of the pivot, the flanges are drawn together without clamping the boss 182 of the lever 50, the said boss being situated between the enlarged front disk of 65 the pivot 49 and the flange 180 of the bush

144. It is thus possible to adjust the pivot 49 at different levels in the slot 49^b.

The bushing 143, which is freely movable in the slot 49^b of the bearing 49^a, is provided with an elongated slot 184 at its lower portion. Projecting upwardly through bores in the lower arm of yoke 185 are two bolts, 146 and 147, threaded at one of their ends, and provided at the opposite ends with heads which enter the slot 184 in the bushing 70 143. The threaded ends of the bolts 146 and 147 are engaged by nuts 186. By moving the nuts up or down on the threaded ends of the bolts 146, 174, the heads of the latter will allow to be raised or lower the bushing 143 75 in the slot 49^b. After the bushing 143 has been thus adjusted, the nut 145 is screwed 80 home, thus clamping the bushing 143 in adjusted position.

By these means, the operation *i. e.* the preliminary blowing of the glass ball, can be 85 regulated by the adjustment of the roller 48 in connection with the bearing bolt 49 without affecting the total capacity of the machine and the other mechanism. The possibility is thus afforded that the preliminary blown glass ball, according to the quality or nature of the glass mass, is cooled in the preliminary mold until the opening of the latter, in order that the same permits a substitution of the preliminary or finishing 90 blowing mold for the head mold and enables 95 a good distribution of the glass, which is of special importance.

The disk 24 of the shaft 16 has a cam 24^a 100 (Fig. 6) which is adapted to engage with a roller 62 of a lever 63^a. The lever 63^a is adapted to rotate loosely on the shaft 79 mounted horizontally on the machine frame and has a projecting bolt or pin 63^b, which 105 extends into the longitudinal hole of a lever arm 63^c keyed on to the preliminary mold shaft 30. Owing to the raising of the roller 62 by the abutment 24^a of the disk 24, the lever arm 63^c will also be raised through 110 the medium of the bolt 63^b, so that the shaft 30 will be returned with the levers 31 and 32 mounted thereon. Since the levers 31 and 32, as above described, are connected to the halves 41 (Fig. 2) of the preliminary mold, 115 the preliminary mold 41 will be opened by the rearward movement of the levers 31 and 32.

At the moment when the roller 62 of the lever 63^a (Fig. 6) is forced up by the cam 120 24^a, the roller 56 (Fig. 10) of the lever 58 also leaves the abutment of the cam disk 18, so that the levers 61 and 61^a (Fig. 1) connected to the closing lid or cover 60 of the preliminary mold will be returned to their 125 position of rest by the weight 147 (Fig. 10) suspended to the connecting rod 59 and the closing lid or cover 60 will be lifted off the preliminary mold 41.

The cam disk 20 (Fig. 9) of the shaft 16 130

is also provided with a groove 64 (Fig. 3) wherein the roller 65 of a cranked lever 66 runs. The latter is rotatably mounted on the pin 67 and connected with its free end by 5 a rod 68 (Fig. 9) to a toothed segment 69, which oscillates on a pin 70 of the machine frame. The segment engages with a toothed wheel 71 keyed on to a shaft 72. The shaft 72 is mounted in the bearing 74 of the machine frame and also secured to the frame 10 73 of the head mold 47 (Figs. 9, 11 and 12). By the rotation of the toothed segment 69, the frame of the head mold can therefore be swung forwardly out of the position in 15 Fig. 9 at an angle of 180°. This takes place when the roller 65 of the lever 66 slides in the groove 64 of the disk 20 from the highest step to the lowest one. By means of the lever transmission, the toothed segment 69 20 and the shaft 72 with the head mold frame secured thereto will be rotated, so that the head mold 47 passes out of the preliminary mold 41 into the finishing mold 75 (Fig. 2).

The finishing blowing mold 75 is mounted 25 on an adjustable table 76 (Fig. 6) of the main table 2. During the rotation of the shaft 16, the disk 26 (Fig. 6) bears with its abutment against the roller 77 of a cranked lever 78. The latter is fixed on the 30 shaft 79 and carries at the ends of its two arms the rollers 77 and 117, both of which roll off the disk 26. By means of the aforesaid rotation of the disk 26, the roller 77 is moved forward out of its position in Fig. 35 6, whereby the shaft 79 and also the lever 80 (Figs. 1 and 2) mounted on the other end of the shaft 79 are rotated. The two lever arms 78 and 80 are connected by the two rods 81 and 82 (Fig. 2) and these engage 40 with cranked levers 83 and 84 adapted to oscillate on the pins 85 and 86. The free arms of the cranked levers 83 and 84 are connected to the halves 75 of the finishing mold by intermediate pieces 87 and 88 (Fig. 45 2). By means of the above-described movement of the lever arm 78, rotation of the shaft 79 and the resultant rotation of the cranked levers 83 and 84, the finishing blowing mold will be closed.

50 A roller 99 of a double-armed lever 100 is moved by the cam of the disk 17 (Fig. 10) mounted on the shaft 16. The lever 100 oscillates on a horizontal pin 101 of the machine frame and is connected with its free end through the interposition of a spiral spring to the piston rod 102 of a piston 103 (Fig. 10), which moves to and fro in a cylinder 104 mounted on the machine frame. During the downward movement of the arm 55 of the lever 100 carrying the roller 99, the piston 103 will therefore be forced upward in the cylinder 104.

By means of the cam of the disk 19 (Fig. 10) mounted on the shaft 16, the roller 105 60 of a double-armed lever 106 is moved to

and fro. The double lever 106 is adapted to oscillate on the pin 107 on the machine frame. The one end of the lever 106 carries an adjustable weight 106a (Fig. 10) while the other end of the lever engages 70 with the vertical rod 108 adapted to move the blowing head 113 (Fig. 1). The blowing head 113 communicates through tube 112, pipe 115 and tube 116 (Fig. 1) with the cylinder 104. The upward and downward movement of the blowing head is effected by two parallel lever arms 114, 114a, which are connected to a standard 110a of the machine frame (Fig. 1). The previously mentioned rod 108 engages with the lower 80 lever arm 114, so that by the action of the cam disk 19, the blowing head 113 firmly bears on the head mold 47 which latter is now seated in the closed finishing blowing mold 75.

85 During the ascent of the piston, the air contained in the cylinder 104 above the piston 103 is driven through the piping into the blowing head 113 and finishing mold 75, whereby the finishing blowing of the preliminarily manipulated bottle is effected.

90 The cranked lever 78 (Fig. 6) is so formed that when the roller 77 moves on the high step of the cam of the disk 26, the roller 117 mounted on the other arm of the lever 78 95 bears against the smallest periphery of the cam of the disk 26. If, therefore, the roller 77 leaves the cam, the cranked lever 78 will return to its initial position. Now since the shaft 79, on which the lever 78 is keyed, 100 is also returned with the lever 80, the rods 81 and 82 (Fig. 2) will be drawn back and consequently the finishing blowing mold 75 connected to the rods 81 and 82 will be 105 opened again.

110 When the roller 105 of the double-armed lever 106 (Fig. 10) has left the abutment of the cam disk 19, the lever 106 will immediately return to its position of rest in consequence of the weight 106a. The rod 108, the lever 114 and the tube 112 with the blowing head 113 will thus also return to the position of rest i. e. the blowing head will be lifted off the head and finishing mold.

115 During each revolution of the disk 21 (Fig. 9) of the shaft 16, the cam of the disk bears against an abutment 118a of the lever 118. The lower end of the lever is rotatably mounted on a pin 119 of the machine frame, while the other end of the lever 118 is connected by a connecting piece 120 to a cranked lever 122 adapted to oscillate on a pin 121. The free arm of the cranked lever 122 (Fig. 9) carries a projecting pin or bolt 123, 120 which, when the head mold bears on the 125 finishing blowing mold, can abut against the projecting arm 124a of a T-shaped cranked lever 124 mounted on the head mold frame (Figs. 1, 11 and 12). The two-part head mold 47 (Figs. 11 and 12) consists of the 130

two halves 125 and 126. The half 125 is carried by two rods or bolts 127 and 128, which are guided in the frame 73 and united by a traverse or yoke 130. The other half is secured to the pin or bolt 129 also guided through the frame 73 (Fig. 12). The yoke 130 engages with a rod 131 (Figs. 9 and 11) connected to the cranked lever 124. To the rod 129 is connected a loop 132, which is also connected to the cranked lever 124 by a rod 133. The cranked lever 124 is secured to the pin or bolt 134, which is mounted in the frame 73 and carries at its end spiral springs 135, whose one end bears against an abutment of the frame 73.

If, in consequence of the action of the cam disk 21 (Fig. 9), the lever 118 and the cranked lever 122 are set in rotation, the bolt 123 of the cranked lever 122 swings out and abuts against the T-shaped cranked lever 124 (Fig. 11) which latter is forced upward. By the rotation of the cranked lever 124, the rods 131 and 133 (Fig. 11) connected therewith will be moved in opposite directions, and also the yoke 130 and loop 132 with the pins 127 and 128 and 129 secured thereon. Consequently, the halves 125 and 126 of the head mold move apart, so that the head mold 47 will open and release the bottle head 160 (Fig. 11) which was hitherto inclosed in the head mold.

As soon as the head mold 47 is open, the roller 65 (Fig. 9) of the cranked lever 66, which hitherto ran on the smallest periphery in the groove 64 of the disk 20, will be forced upward *i. e.* returned to its initial position on the groove 64 assuming a larger diameter. The cranked lever 66 will thereby be rotated, the rod 68 pulled, and the toothed segment 69 swung back so that the toothed wheel 71 will always be rotated with the shaft 72. The head mold frame 73 secured to the shaft 72 will therefore be turned back at an angle of 180° *i. e.* the open head mold 47 is lifted off the finishing blowing mold 75 and bears again in the preliminary mold 41. As soon as the head mold 47 is lifted off the finishing mold, the cam of the disk 21 (Fig. 9) leaves the abutment 118a of the lever 118, so that the latter returns to its position of rest. The cranked lever 122 also falls back and the pin or bolt 123 releases the arm 124a of the cranked lever 124 mounted on the head mold frame, so that the lever 124 with the parts hinged thereto returns to the position of rest in consequence of the tension of the spiral springs 135 *i. e.* the halves of the head mold are closed again.

The bottom or base 75a of the finishing blowing mold 75 is mounted on an adjustable pin or bolt 136 of the table 76 (Fig. 6). The bolt or pin 136 is secured to the shaft 137 (Fig. 8) which is rotatably mounted on the table 76. On the shaft 137 is mounted a lever arm 138, which is connected by a

bent rod 139 to a lever arm 140 rotatably mounted by a pin 141 on the table 2 of the machine (Fig. 8). The lever 140 is so arranged that the roller 142 (Fig. 8) mounted thereon bears against the disk 25 of the shaft 16, so that the lever 140 can be forced away by the abutment of the disk 25. Through the connection with the rod 139, the shaft 137 is rotated and the pin or bolt 136 with the base or bottom of the blowing mold is brought into an inclined position, so that the finished bottle standing on the bottom is led away preferably into a channel or chute from which it can be caught by the workman by means of a shovel or other suitable means.

The operation of the present machine and the development of a bottle are as follows:

When the head mold 47 has been placed in the preliminary mold plate by the respective mechanism, the preliminary mold 41 closes under the action of the disk 23, roller 28, lever 29, shaft 30, levers 31 and 32, rods 33 and 34 and cranked levers 35 and 36. At the same time, the neck core 46 is brought into the head mold 47 through the medium of the disk 22, cranked lever 43 and core carrier 45. The liquid glass mass is now filled into the preliminary mold by a workman. A suction action is thereupon exerted on the glass mass by the piston 52, which is drawn downward in the cylinder 53 by the action of the disk 24 (Fig. 8) roller 48 and cranked lever 50, so that the glass is drawn around the neck core 46, whereby the neck opening of the bottle is formed. By means of the cam 95 of the disk 24 and the lever mechanism connected therewith, the cutting off knives 96 and 97 (Fig. 7) have meanwhile moved toward each other. These knives cut off the glass ball from the gathering iron of the workman, or the cutting off may also be effected by the workman by means of hand lever 93a.

The piston 52 has meanwhile reached its low position. The closing cover or lid 60 of the preliminary mold is fixed to the preliminary mold 47 by the roller 56, disk 18 (Fig. 10) cranked lever 58, rod 59 and the levers 61 and 61a. The roller 42 (Fig. 6) of the cranked lever 43 thereupon leaves the cam of the disk 22, whereby the neck core 46 drops out of the head mold 41.

The piston 52 (Fig. 8) will now be forced upward in its cylinder 53 by the lever mechanism connected to the piston, so that the previously drawn in air is now forced into the opening in the glass (left behind by the neck core 46) whereby the preliminary blowing of the bottle is carried out until the piston 52 has reached its highest position (Fig. 8) or position of rest.

The roller 28 (Fig. 6) of the lever 29 then leaves the cam of the disk 23, the roller 62 (Fig. 6) will be forced upward by the

cam 24^a of the disk 24, so that the pin or bolt 63^b strikes against the lever arm 63^c and the shaft 30, the levers 31 and 32, rods 33 and 34 and cranked levers 35 and 36 are set in rotation, and consequently the preliminary mold 41 will be opened. At the same time, the closing cover 60 of the preliminary mold will be lifted off the preliminary mold 41 and the roller 56 (Fig. 10) will leave the abutment of the disk 18 and the rod 59 with the lever mechanism thereon will be pulled down by the weight 147.

When the preliminary mold 41 is quite open, the roller 65 of the cranked lever 66 will be moved through the groove 64 of the disk 20 (Fig. 9), so that the adjoining toothed segment 69 and toothed wheel 71 will be rotated and consequently, the head mold 47 with the preliminary blown bottle will be swung out of the open preliminary mold, turned at an angle of 180° and brought into the finishing blowing mold 75.

The finishing blowing mold 75 is now closed by means of disk 26 (Fig. 6), roller 77, cranked lever 78, shaft 79, lever 80, rods 81, 82 and cranked levers 83, 84. At the same time, the blowing head 113 is now fixed on the head mold 47 in the closed finishing blowing mold 75 by the operation of the rod 108 through the medium of the lever 106, roller 105 and cam disk 19 (Fig. 10).

By means of the disk 17 (Fig. 10) roller 99 and lever 100, the piston 103 is forced upward in the cylinder 104, so that air is forced into the preliminary blown glass ball through the pipe 116, tube 115, pipe 112 and blowing head 113, whereby the finished blowing out of the bottle takes place. The roller 105 then leaves the abutment of the disk 19 (Fig. 10) and through the weight 106^a and leverage on the rod 108, the blowing head 113 is lifted off the head and finishing blowing mold and returned to its position of rest (Fig. 1).

45 By the abutment of the disk 21 (Fig. 9) the lever 118 and the cranked lever 122 connected therewith will be rotated, so that the pin or bolt 123 of the lever 122 will strike against the arm 124^a of the cranked lever 124 and consequently, the halves of the head mold will open and release the finishing bottle, which remains in the closed blowing mold 75. At the same time, when the head mold 47 opens, the head mold frame 73 will be rotated by the toothed segment 69 and the mechanism connected therewith, so that the preliminary mold is lifted off the finishing blowing mold and swings back again into the preliminary mold. During the ascent of the head mold frame, the abutment of the disk 21 (Figs. 9, 1) leaves the projection 118^a of the lever 118, whereby the latter and also the cranked lever 122 with pin 123 move backward immediately and release the T-shaped cranked lever 124 of the

head mold frame 73 and consequently, the halves of the head mold are closed by the action of the spiral springs 135.

The closing of the preliminary mold, the filling in of the liquid glass mass and the preliminary manipulation of the glass bottle meanwhile take place in the above-described manner.

Shortly before the bottle is finished in the preliminary mold, the finishing mold 75 opens again through the medium of the roller 117 (Fig. 6) of the cranked lever 87 and the mechanism connected therewith. Through the action of the disk 25 (Fig. 8) lever 140 and shaft 137, the base or bottom 80 of the blowing mold is brought into an inclined position and consequently, the finished bottle slides down the same.

The described operation for making a bottle is carried out during a single revolution of the driving shaft 16 and also during a revolution of the whole machine about the central column 5. Since the machine may be fitted with four or more arms, or arranged as single machines, several preliminary as well as finishing molds are adapted to operate simultaneously. Two men are sufficient for attending to such a four-armed machine and since the single mold sets are independent of each other and not dependent on any dimensions, the various sizes and shapes of bottles can be made simultaneously.

The machine is rendered operative and inoperative by a coupling such as a cone coupling, which is preferably provided on the driving shaft 16. In connection with a four-armed machine, the single machine sets may also be thrown out of gear by couplings, so that, if desired, only three or less sets are in operation.

I claim:

1. In a bottle forming machine, the combination of a main driving shaft, a preliminary forming mold, means connected with said main shaft and driven therefrom for opening and closing the said mold, a column extending vertically upward from the machine frame, a pair of arms pivoted to said column, one of said arms having one end pivoted to said column and the other arm being pivoted intermediate its ends to said column, a closing lid carried at one end of said arms, a vertically reciprocable weighted rod pivotally attached to the opposite end of one of said arms, means connected with said main shaft and driven therefrom for elevating said rod to depress the closing lid in position over the preliminary mold, a final blowing mold, means connected with said main shaft and driven therefrom for opening and closing the same, a neck forming mold, and means connected with said main shaft and driven therefrom for swinging said neck forming mold alternately into

operative relation with said preliminary mold and said final mold.

pivots attached to the opposite end of said intermediately pivoted arm, and means connected with and driven from the main shaft for raising said rod at intervals to depress the closing lid in position over the preliminary mold.

6. In a bottle forming machine, the combination of a main driving shaft, a sectional preliminary forming mold, means connected with and driven from the main shaft for moving the sections of said mold toward and from each other, a column extending vertically upward from the machine frame, arms pivoted to said column, one of said arms having one end pivoted to the column and the other arm being pivoted intermediate its ends to the column, a closing lid pivoted to one end of said arms, a vertically reciprocable rod pivotally attached to the opposite end of one of said arms, means connected with and driven from the main shaft for raising said rod to depress the closing lid in position over the preliminary mold, a sectional final blowing mold, means connected with and driven from the main shaft for moving the sections of the final blowing mold toward and from each other, a neck forming mold comprising a frame, parallel rods in said frame, mold members carried by said rods, and means for normally retaining said members in closed position, and means connected with and driven from the main shaft for swinging said neck forming mold in the arc of a circle alternately into operative position with the preliminary mold and the final mold.

7. In a bottle forming machine, the com-

bination of a main driving shaft, a sectional preliminary forming mold, means connected with and driven from the main shaft for moving the sections of said mold toward and from each other, a column extending vertically upward from the machine frame, arms pivoted to said column, one of said arms having one end pivoted to the column and the other arm being pivoted intermediate its ends to the column, a closing lid pivoted to one end of said arms, a vertically reciprocable rod pivotally attached to the opposite end of one of said arms, means connected with and driven from the main shaft for raising said rod to depress the closing lid in position over the preliminary mold, a sectional final blowing mold, means connected with and driven from the main shaft for moving the sections thereof toward and from each other, a neck forming mold comprising a frame, parallel rods in said frame, mold members carried by said rods, and means for normally retaining said members in closed position, means connected with and driven from the main shaft for swinging said neck forming mold in the arc of a circle alternately into operative position with the preliminary mold and the final mold, and means connected with and driven from the main shaft for separating the parts of said neck forming mold when the same is over the final blowing mold.

In testimony whereof I affix my signature in presence of two witnesses.

JOHANN MAINZER.
